UNITED STATES PATENT OFFICE.

COLIN CAMPBELL, OF RUTHERFORD, NEW JERSEY.

FURNACE-ARCH CONSTRUCTION.

957,494.

Specification of Letters Patent. Patented May 10, 1910.

Application filed December 30, 1909. Serial No. 535,652.

To all whom it may concern:

Be it known that I, COLIN CAMPBELL, citizen of the United States, residing at Rutherford, county of Bergen, State of New Jersey, 5 have invented certain new and useful Improvements in Furnace-Arch Construction, of which the following is a specification.

My invention relates to improvements in arches and more particularly to arches used 10 in furnace construction.

The objects of my invention are to simplify and strengthen the construction of arch plates and the fire blocks used in connection therewith as now used for the fire- 15 boxes of steam boiler furnaces.

A further object of my invention is to provide for the easy removal of the fire-blocks, as the same become burned out or cracked by the intense heat of the fire, without disturbing the remaining blocks or necessitating the removal of any portion of the 20 furnace structure.

With these and other objects in view my invention consists in the novel construction 25 and arrangement of parts as hereinafter described and as pointed out in the accompanying drawing, in which:

Figure 1 is a front elevation of a fire-box partly broken away, showing my improved 30 arch with some of the fire-blocks mounted therein. Fig. 2 is a front elevation of my improved metallic arch. Fig. 3 is a transverse section of the same. Fig. 4 is a bottom plan view of Fig. 2. Fig. 5 is a side elevation of one of my improved fire-blocks. Fig. 35 6 is a rear view thereof. Fig. 7 is a cross section of the same. Fig. 8 is a top plan of Fig. 5.

In Fig. 1 of the drawing I have shown 40 my improved metallic arch plate A mounted over the fire-box C of a furnace and having a number of my improved fire-blocks B set into the arch plate as hereinafter described. The metallic arch plate A is preferably made 45 of cast iron, and is made in the shape of a segment of a cone and has, cast integral therewith, dove-tailed tongues a, cast a sufficient distance apart to allow for the reception of two fire-blocks between each two 50 tongues. The tongues are square at their upper ends where they join the casting, as at a¹, and they gradually spread out to a dove-tail, as will be readily seen in the accompanying drawing. The purpose of this 55 squared portion is to allow for any imperfection in the corners of the casting, as will

be hereinafter described with reference to the fire-blocks.

B are the fire-blocks, made of refractory material, to be used with this casting and 60 they taper toward the rear end, the purpose of which will be hereinafter described. The blocks B are provided with a dove-tailed recess d on one side thereof, adapted to fit the tongue in the arch plate and having the 65 other side recessed as at e the recess being formed between the ends of the block and not extending the whole length thereof. The dove-tailed recess runs almost the whole 70 length of one side of the block and has the part above said recess cut away, as at d¹, 75 which corresponds to the square part a¹, of the tongues in the arch plate. This peculiar construction of the tongues and fire-blocks is to allow for any imperfection in the corners, where the tongues meet the arch plate, during the casting operation. Two of these blocks have corresponding recesses in their 80 sides and are held together by a cement binder or other suitable binding material and are then slid into place between the 85 tongues in the arch plate. The front ends of the blocks terminate in an upwardly projecting lip or flange as shown at g for covering the arch plate when they are in position.

It is evident from the foregoing description that the metallic arch plate A is first put into position above the fire-box of a furnace and the fire-blocks B then slid into position between the tongues. As before 90 stated the arch plate is cone shaped, or is the segment of a cone, and the fire-blocks being tapered, will, when forced into position, be wedged firmly and securely in place and the lip or flange g will cover the front 95 of the plate, and lie flush with the brick-work of the furnace. Should any of the blocks become burned out it is only necessary to remove them and insert a new pair in place, without disturbing the rest of the 100 arch. If for any reason the blocks are too wide to fit between the tongues the part surrounding the recesses e may be chipped off, or cut down, to enable the blocks to be put 105 in position.

From the above description it will be seen that applicant's invention possesses many advantages over arch plates and fire-blocks heretofore used as the dove-tailed form of tongues and fire-blocks possess greater 110 strength and holding qualities than the T and other forms of retaining tongues.

I do not limit my invention to a spring or curved arch, but desire to employ it wherever it can be advantageously used.

Having thus described my invention what 5 I claim and desire to secure by Letters Patent is:

1. In arch construction the combination with an arch plate, said arch plate being a segment of a cone, of holding means cast 10 integral therewith and tapered fire-blocks removably held and secured by said holding means.
2. In arch construction the combination with an arch plate, said arch plate being a true segment of a cone, dove-tailed tongues 15 cast integral with said arch plate and correspondingly grooved fire-blocks removably held and secured by said dove-tailed tongues.
3. In arch construction, the combination 20 with an arch plate, said arch plate being a true segment of a cone, dove-tailed tongues cast integral with said arch plate, tapering fire-blocks having correspondingly dove-tailed recesses adapted to be removably secured in said arch plate.
4. In arch construction, the combination 25 with an arch plate having dove-tailed

tongues cast integral therewith, a pair of fire-blocks held together by a binding agent and removably secured in said arch-plate 30 between said tongues.

5. In arch construction, the combination with an arch plate having dove-tailed tongues cast integral therewith, a pair of fire-blocks held together by a binding agent, 35 and having dove-tailed recesses, adapted to receive the aforementioned tongues and removably held and secured between said tongues.

6. In arch construction, the combination 40 with an arch plate, said arch plate being a true segment of a cone, a pair of fire-blocks having recesses, said recesses adapted to receive a binding agent, and means for removably securing said fire-blocks in said 45 arch plate.

In testimony whereof I have hereunto set my hand in presence of two subscribing witnesses.

COLIN CAMPBELL.
